UNITED STATES PATENT OFFICE.

ANDREW ENGLE, OF NEWTON, IOWA, ASSIGNOR OF ONE-HALF TO JAMES MAINE, OF DES MOINES, IOWA.

MEANS FOR DISPOSING OF WASTE PRODUCTS AND UTILIZING COMPONENTS THEREOF.

Application filed August 24, 1925. Serial No. 52,195.

The object of this invention is to provide an improved means for disposing of sewage, including night soil, in a sanitary and economical manner.

5 A further object of this invention is to provide an improved means for disposing of waste material such as sewage, including night soil, and treating it in such a way that parts of it may be utilized for a fertilizer or 10 the like.

A further object of this invention is to provide an improved construction for a container or septic tank into which sewage may be deposited and treated in a way to purify 15 and clarify it and permit its use as a fertilizer.

A further object is to provide a convenient way for drawing off liquid parts of the sewage, clarifying and purifying the 20 same, and utilizing such parts as a fertilizing means.

With these and other objects in view, my invention consists in the construction, arrangement and combination of elements 25 hereinafter set forth, pointed out in the claim and illustrated by the accompanying drawing, in which—

The view, on the drawing, is a longitudinal section, illustrating, more or less diagrammatically, the construction of my improved devices.

In the construction of the means as shown the numeral 10 designates generally a container or tank which may be made of concrete and located beneath the surface of the soil, at such depth as to prevent freezing. The tank 10 is divided by a transverse partition 11, of soft brick or the like, into an initial compartment 12 and a larger compartment 13. An inlet pipe 14 discharges into the upper portion of the initial compartment 12 and preferably is provided with a trap 15, and it is designed to receive sewage from any place such as the toilets of a school, 45 house or other public or private building. The solid portions of the sewage are retained for a time in the compartment 12, but the liquid portions may seep through the soft brick partition 11 into the compartment 13. 50 The respective compartments 12 and 13 are provided with manholes 16 and 17, having covers 18 and 19 with their rims extending into annular seals 20 and 21 designed to be filled with a liquid, which may be of non-freezing character when required.

If desired a pump such as 22, designed for manual operation or otherwise, may be mounted on and communicate with the interior of the compartment 13 near its bottom, said pump being provided with a discharge pipe 23 leading to the inlet pipe 14 above the trap 15. The pump may be used to draw liquid from the compartment 13 for the purpose of flushing the inlet pipe 14 and its trap, to save too great dilution of the contents of the tank by flushing with water.

A siphon pipe may be provided, here designated by the numeral 24, leading from a point near the bottom of the compartment 13 upwardly therein, then through the wall 70 to any desired location and then downwardly and discharging at a point lower than its inlet end. The siphon pipe may be provided with a hand operated shutoff valve 25 at any suitable location. In the present instance I have shown the siphon pipe 24 discharging into a filtering tank 26 which may also be constructed of concrete and placed in any suitable location, preferably under 75 ground. This tank is open and has a horizontal partition or false bottom 27, of soft brick or other suitable porous material. Beneath the false bottom 27 there is a bed of filtering sand 28 or the like which rests on the bottom of the tank. A discharge pipe 80 85 29 leads from the bottom of the tank 26 to any suitable location.

In practical use the waste materials are deposited in the compartment 12 as described and the liquid parts seep through the partition 11 and fill the compartment 13 to a level corresponding to that in the first compartment. The compartments being closed and sealed, the bacteria present in the material operate to the production of nitrates without decomposition and putrefaction. The material may be allowed to remain in the closed tank for any desired time within the capacity thereof, and may from time to time be removed from the compartments 12 and 13 90 95 through the manholes 16 and 17 respectively, by means of pumps or the like. As the solid material in the compartment is moist because of the presence of part of the liquid components therein, it does not decompose, rot or dry out and is easily handled by pumping or dipping. The solid and liquid parts so removed may be utilized as fertilizer in their state as when removed, or they may be further treated to produce comminuted and 100 105 110

finished fertilizer by any method; or the solid portions may be dried and treated to produce a fuel by any desired method, which methods form no part of my present invention.

A pipe 30 may be provided, leading into the compartment 13 from any suitable source, which is employed to convey into the contents of said compartment at times an antiseptic substance or chemical of any suitable nature for killing dangerous or noxious bacteria, germs or microbes, especially when the waste material is thought to contain disease germs. The pipe 30 terminates in a perforated pipe 31 leading along the bottom of the compartment by means of which the antiseptic substance is diffused through the contents of the compartment. The pipe 30 is controlled by a valve 32.

Sometimes it may be desirable to draw the liquid contents from the compartment by means of the siphon pipe 24, which may be done when the liquid level rises above the horizontal portion of said pipe, by opening the valve 25. The liquid contents of the compartments are discharged into the filtering tank 26 upon the false bottom 27, which retains any solid matter or sediment which may be present, the liquid passing through the porous material of said bottom to the filter bed 28, where it is further clarified and purified. It may then pass off through the pipe 29 to any suitable place of discharge and may then be placed upon the soil for fertilizing purposes, for which it is very useful.

The liquid in the tank 10 will naturally contain a large amount of ammonia, and this may be removed by distillation and utilized, when the method is used of removing the liquid through the manholes 17 and 16.

The means and devices herein described

will be found very valuable for use in connection with private homes, school buildings, hotels, camps, public or private buildings where many people congregate, and in many other places. It may be used to displace not only the open privy vault or similar structure, but also the so-called modern but highly unsanitary and dangerous methods by which sewage is turned into streams and other bodies of water.

It is obvious that the size and capacity of the tank may be varied greatly in accordance with the need at a specific location; and there is no harm in making it of such size that it need be emptied but once a year, as there is no fermentation or decomposition, no noxious gases to escape, and no odor.

Another benefit and advantage of using this sort of means for disposing of the waste materials, is that it prevents the breeding of flies such as occurs when such material is left in the open, and the consequent spreading of disease germs by them.

I claim as my invention—

In a means for disposing of waste materials and utilizing components thereof including a closed tank divided into two compartments, a supply means comprising an inlet pipe provided with a trap for introducing waste materials to the initial compartment, a part of the liquid component being permitted to pass to the second compartment, and a pump device communicating with the second compartment and adapted to discharge liquid therefrom to the inlet pipe for the purpose of flushing it and the trap and thereby preventing undue dilution of the contents of the tank.

Signed at Des Moines, in the county of Polk and State of Iowa, this 15th day of August, 1925.

ANDREW ENGLE.
